FABRIC PACKAGES

Florence B. Zacks, Columbus, Ohio, assignor to R. G. Barry Corporation, Columbus, Ohio, a corporation of Ohio
Original application Dec. 15, 1958, Ser. No. 780,312. Divided and this application Oct. 17, 1960, Ser. No. 62,904

6 Claims. (Cl. 206—19.5)

This invention relates to special packages and more particularly to a fabric package adapted to serve as an automotive accessory providing ready and convenient accessibility for the driver of a car.

This application is a division of my copending application Serial No. 780,312, filed December 15, 1958.

The general object of the invention is the provision of a novel and improved accessory package of this class which, by ingenious correlation of properties of both the contained fabric article and its enveloping covering, affords an easily manufactured, efficiently useful, and readily accessible product, while at the same time preserving its neat appearance and ornamental character.

While susceptible of combining in its construction or assembly fabric articles of different characters and functions, the invention in its illustrative embodiment, includes a heel guard for the protection of the shoes, especially of women drivers, and a novel frictional envelope embodying means for the suspension of the package in a convenient position in the vehicle, for example, under the instrument panel.

There have been many prior provisions of such heel protectors and there have been a great number of different materials used in their construction, from metal and hard fiber to leather and fabric; however, no special and convenient means for stowing the protectors when not in use has been suggested.

It is therefore an object of the present invention to provide a novel and improved accessory of this character which incorporates certain advantageous features of construction which enhance the utility of the device as a protector of heels of shoes against abrasion and scuffing in the operation of the brake and accelerator pedals, and which also possesses properties which cooperate to provide convenient and effective means for stowing the heel protector when not in use.

The invention in its suggestive embodiment contemplates the provision of a pocket-like or scoop-like heel protector constructed of different fabrics in its various parts. The rearward or major portion of the member is made of a durable close-woven fabric preferably in laminated form, the inner and outer layers being of cloth and an intermediate lamination of foam rubber or equivalent foam plastic material which not only strengthens the fabric but stiffens it to a slight degree, adding somewhat increased bulk which has a function which will be presently described. The side portions of the device are made of softer, more flexible fabric such as terry cloth in one embodiment, and an elastic mesh material in another embodiment.

The other important element of the package structure comprises a substantially rectangular fabric envelope closed along three of its margins but open along the fourth, the envelope adapted to be suspended in inverted position with the open mouth downward. This envelope or bag element is preferably made of an ornamental fabric lined with a relatively thin layer of foam rubber or equivalent foam plastic material for the purpose of increasing the friction between the enclosed member itself and the inner walls of the envelope, when the member is folded or wadded and stuffed into the envelope.

The member is thus not only securely retained in posi-

2

tion for use when needed, but is very readily removed therefrom by a mere downward pull on the member, portions of which may be allowed to protrude through the mouth of the bag or envelope if desired.

Within the broader scope of the invention, the enclosed fabric members or articles may be other than the heel protector described, provided only that they are relatively light in weight, and are of material of somewhat frictional surface characteristics and capable of being folded or wadded to form a mass of considerable bulk as related to the capacity of the envelope portion.

Other objects and features of novelty will be apparent from the following specification when read in connection with the accompanying drawings in which one embodiment of the invention is illustrated by way of example.

In the drawings:

FIGURE 1 is a somewhat diagrammatic view in vertical longitudinal section through the dash portion of an automobile, one foot of the driver being shown with a fabric heel protector member applied to the heel of the shoe, and an envelope member constituting part of the novel package suspended from a portion of the instrument panel of the car;

FIGURE 2 is a perspective view showing one form of heel protector element, being an example of the fabric accessory forming a part of the inventive concept;

FIGURE 3 is a view in rear elevation of a fragmentary portion of the dash of the automobile and showing the novel fabric package suspended therefrom; and

FIGURE 4 is a fragmentary transverse sectional view taken on line 4—4 of FIGURE 3.

Referring now to FIGURE 1 of the drawings, the numeral 10 is applied to the sloping front floorboard of an automobile, the numeral 11 to the dash, and the numeral 12 to the instrument panel. The accelerator pedal is shown at 15 with the connecting mechanism 16 extending through the floor panel 10. The foot of a woman driver is encased in a low heel walking shoe indicated at 20 and the heel portion of the shoe is encased in a heel protector of novel construction which is the subject of the above mentioned co-pending application, and is indicated in its entirety by the numeral 25. This form of heel protector is also denoted by the same reference numeral in FIGURE 2.

In this particular protector the rear panel portion indicated at 27 is of laminated construction having an outer layer of fabric 28 which should be of durable and preferably ornamented construction and manufacture, and an inner fabric layer 29 which may be of plain material.

Between these layers is cemented a thin layer of foam rubber or foam plastic material 30. A side and bottom panel of the protector 25 is shown at 32 and comprises an area of elastic webbing which, as disclosed in FIGURE 1 of the drawings, underlies the heel of the shoe and extends up the sides of the heel portion of the upper. The portion 32 is sewn to the portion 27 along the seam 33.

The outer marginal portions of both of the areas 27 and 32 are gathered and a marginal tape 34 is secured along the edges of the portion 32 while a similar tape 35 is stitched along the marginal portions of the area 27, the tape 35 being preferably extended as at 36 and 37 to provide securing means for the device, the tapes 36 and 37 being tied together as at 39 in FIGURE 1. The tapes are preferably made of elastic material to aid in snapping the protectors onto the heels and retaining them snugly in place.

For suspending the heel protector element 25 in readily accessible position when not in use, a novel packaging expedient is provided embracing the heel protector together with a bag or envelope indicated generally at 40. The bag is formed of two panels of material 41 which are stitched and taped along three margins as at 42, and the

lower side of the device 40 is open, the margins of the opening being taped as at 43 around the mouth thereof.

In a preferred embodiment of the invention a loop of elastic fabric 45 is secured at one end to the central portion of the upper edge of the envelope and the opposite end is detachably secured to the envelope as by means of a snap fastener 46. This loop may be supported from a hook 48 positioned below the instrument panel, or the elastic loop may be snapped around the steering wheel, the elastic nature of the loop enabling it to expand to fit steering wheels of different thicknesses. The envelope 40 is also laminated and consists of the outer fabric layer 50 and the inner sponge rubber or sponge plastic material 51, both laminations being embraced by the marginal tapes 43 and sewed as at 52, this being clearly shown in FIGURE 4 of the drawings.

When removed from the shoe, the protector 25 is folded and wadded together as clearly shown in FIGURES 3 and 4 of the drawings and stuffed into the open mouth of the envelope 40. The bulk of the protector and the friction provided by the foam lining 51 of the envelope effectively prevent the protectors from falling from the envelope, but the protruding portions of the protector may be readily grasped for removal when the protector is needed.

There is thus provided by the present invention a novel accessory package featured by the use of an inverted open mouthed envelope having a frictional inner surface together with the rather bulky wadded fabric accessory member retained therein against the force of gravity, and the entire package suspended within convenient grasp of the driver of a vehicle.

It is understood that various changes and modifications may be made in the embodiment illustrated and described herein without departing from the scope of the invention as determined by the following claims.

Having thus described the invention, what is claimed as new and desired to be secured by Letters Patent is:

1. An accessory package for ready accessibility by motorists or the like comprising, in combination, a flexible lightweight fabric accessory member, and an envelope closed at its top and side edges but having a permanently open downwardly directed bottom edge, for supporting

said accessory member, as for example, beneath the instrument panel of an automobile; the envelope having an inner surface of frictional material, the accessory member being wadded together and compressed, and contained

5 within the inverted envelope, the bulk of the wadded accessory member being only slightly less than the capacity of the envelope, whereby the accessory member is retained within the envelope by means of the frictional contact between said member and the inner surface of the envelope.

2. The accessory package as set forth in claim 1 in which the envelope is of multi-ply material, the outer exposed lamination being of fabric and the inner lamination being a layer of foam rubber.

15 3. The accessory package as set forth in claim 1 in which at least a portion of the accessory member is of foam rubber, this adding to the resilient bulk of the member for better retention within the envelope.

4. For use in suspending a fabric accessory, as for example, beneath the instrument panel of an automobile, an envelope closed at its top and side edges but having a permanently open downwardly directed bottom edge, and hanger means secured to the closed top edge of said envelope for suspending it in such inverted position, the envelope being of fabric and having an inner lining of foam rubber, the frictional nature of the foam rubber lining serving to retain light fabric accessories within the inverted envelope against the force of gravity.

25 5. For use in suspending a fabric accessory, as for example, beneath the instrument panel of an automobile, an envelope closed at its top and side edges but having a permanently open downwardly directed bottom edge, and hanger means secured to the closed top edge of said envelope for suspending it in such inverted position, the envelope being of fabric and having an inner lining of foam rubber, the frictional nature of the foam rubber lining serving to retain light fabric accessories within the inverted envelope against the force of gravity.

30 6. The suspension means set forth in claim 5 in which the envelope is of fabric and having an inner surface of frictional material whereby it serves to retain light fabric accessories within the inverted envelope against the force of gravity.

35 7. The suspension means set forth in claim 5 in which the envelope is of fabric and having an inner surface of frictional material whereby it serves to retain light fabric accessories within the inverted envelope against the force of gravity.

40 8. The suspension means set forth in claim 5 in which the envelope is of fabric and having an inner surface of frictional material whereby it serves to retain light fabric accessories within the inverted envelope against the force of gravity.
